UNITED STATES PATENT OFFICE.

EUGEN HAGENBUCHER, OF ESSEN, GERMANY, ASSIGNOR TO FRIED. KRUPP AKTIEN-
GESELLSCHAFT, OF ESSEN-ON-THE-RUHR, GERMANY.

LOCOMOTIVE TENDER.

Application filed January 15, 1923. Serial No. 612,871.

To all whom it may concern:

Be it known that I, EUGEN HAGENBUCHER, residing at Essen, Germany, a citizen of the German Republic, have invented a certain 5 new and useful Improvement in Locomotive Tenders, of which the following is a specification.

This invention relates to locomotive-tenders and has for its object to provide a tender 10 the frame of which forms walls of a tank adapted to receive at least part of the water to be carried by the tender.

The accompanying drawing illustrates, as 15 an embodiment of the subject-matter of the invention, a tender of a condensing locomotive.

Fig. 1 is a side elevation of the tender, partly in section,

Fig. 2 a section on the line 2—2 of Fig. 1, 20 seen from above, and

Fig. 3 a section on the line 3—3 of Fig. 1.

The frame of the tender which is supported by two trucks provided with wheels A, possesses beside the main sole bars, not 25 shown in the drawing, two plate girders B which extend throughout the entire length of the tender. The plate girders B are enlarged downwardly in the middle and rigidly connected with each other by means of 30 four L-shaped cross bars C (see particularly Fig. 1). The enlarged portions of the longitudinal girders B constitute the two side walls of a tank D which is disposed between the two trucks A and designed to 35 receive part of the water to be carried by the tender. The tank D is narrowed at the two ends directed towards the trucks A, in order to allow the tank to be extended between the wheels of the trucks A up to the 40 cross bars C which are situated next to the tank D, see particularly Fig. 2. The side walls of the narrowed tank portions are formed by plates E and their end walls by the cross bars C. The bottoms F of the narrowed tank portions are inclined and rise towards the cross bars C. The cover of the tank D is formed by a horizontally arranged plate G which is connected by L-irons ^{g1} with the upper edges of the longitudinal 45 bars B and cross bars C. The tender further carries on both ends of its frame each a

water tank H which is in communication with the water tank D by a pipe J (Fig. 1). Inserted in the pipe J is a valve L controlled by a float K and designed to regulate 55 automatically the supply of the water from the tanks H into the tank D in such a manner that the level of the water in the tank D will be maintained at a constant height as long as water is contained in the tanks H. 60 The re-cooling plant M is mounted on the frame of the tender between the water tanks H. Above one of the two water tanks H there is still provided a space N for receiving coals. 65

The described construction renders it possible to store a relatively large quantity of the water to be carried by the tender in and below the frame of the same. The greater part of the space on the top of the tender 70 frame is thus kept free for the carrying of coal and the mounting of the re-cooling plant so that the tender may be made of a relatively short length. With tenders for condensing locomotives the storing of the water 75 in and below the frame of the tender is even of particular importance inasmuch as the water present underneath the re-cooler, this being a relatively large quantity of water, may take part in the re-cooling process. It 80 is thus rendered possible at the starting of the locomotive at which much steam is consumed, to condense all of the exhaust steam without the circulating cooling water getting excessively heated. 85

In case all of the water carried by the tender should take part in the cooling process, the whole of it has to be stored in the tank D; in this case it will, however, be necessary to mount the frame B of the tender 90 at a plane higher than usual.

I claim:

1. In a locomotive tender, an under-frame comprising longitudinal girders, wheeled trucks at either end of said girders for supporting same, said girders each having a depending wall portion intermediate said trucks, transverse girders connecting said longitudinal girders, and a bottom wall connecting the lower edges of said depending walls and transverse girders for forming a tank. 95 100

2. A locomotive-tender comprising a frame, a tank having its wall formed by the frame and adapted to receive part of the water supply of the tender, water tanks mounted on the frame of the tender, a pipe connecting the water tanks with the first-mentioned tank, a valve inserted in the said pipe and a float arranged in the first-mentioned tank and adapted to control the said valve. ¹⁰

The foregoing specification signed at Cologne, Germany, this 9th day of December, 1922.

EUGEN HAGENBUCHER.
